Primary Examiner — Cynthia R Underwood*(74) Attorney, Agent, or Firm* — Renner, Otto, Boisselle and Sklar, LLPCLAIM

The ornamental design for an over-the-door hanger holder, as shown and described.

DESCRIPTION

FIG. 1 is a top, front, left perspective view of an over-the-door hanger holder showing our new design;

FIG. 2 is a rear elevation view thereof;

FIG. 3 is a front elevation view thereof;

FIG. 4 is a left side elevation view thereof, a right side elevation view being a mirror image of the left side elevation view;

FIG. 5 is a top plan view thereof; and,

FIG. 6 is a bottom plan view thereof.

The broken line showing is for the purpose of illustrating unclaimed portions of the article and forms no part of the claimed design.
